CHERRY-PITTING MACHINE

Tom Toyota Hirao, Pasco, Wash.

Application October 24, 1952, Serial No. 316,677

1 Claim. (Cl. 146—19)

This invention is a cherry-pitting machine. It is one object of the invention to provide a machine which is well adapted for removing the pits from a large number of cherries.

Another object of the invention lies in the provision of a cherry-pitting machine which is provided with multiple cherry-holding sockets and corresponding plungers adapted to pass through the cherries and thus press the pits from the cherries into apertures communicating with the sockets.

Another object of the invention lies in the provision of a cherry-pitting machine having a longitudinally inclined table, a portion of which forms a hopper adapted to contain a quantity of cherries from which the pits are to be removed.

Another object of the invention lies in the provision of a cherry-pitting machine having an inclined table which has depressed tracks leading from its hopper to the sockets which hold the cherries while the pit is being removed.

A still further object of the invention lies in the provision of a cherry-pitting machine which has a plurality of lifters adapted to be shifted into the cherry-holding sockets and thus displace the cherries after the pits have been removed.

Another object of the invention lies in the provision of a cherry-pitting machine which has a plurality of plungers disposed to pass through the cherries in the sockets and remove the pits, said plungers being surrounded by a stripping bar which permits removal of the cherries from the plungers.

These and other objects of the invention will become apparent during the course of the following description.

In the accompanying drawings, forming a part of this specification, and in which like numerals are employed to designate like parts,

Figure 1 is a perspective view of my improved cherry-pitting machine; and

Figure 2 is a longitudinal vertical cross section taken through the machine.

Referring now more particularly to the drawing, I indicate the table of the machine by the numeral 10, and it will be seen that the table is formed of a rectangular piece of wood or other suitable material having a planar upper face 11 and which is supported by front and rear legs 12 and 13, the rear legs of which are longer, thus disposing the table at an incline longitudinally. The marginal side edges of the table 10 are provided with longitudinally extending side rails 14, and the rear edge of the table is provided with an upstanding back plate 15 which extends the full width of the table and is secured thereto. As shown in Figure 2, a re-enforcing rail 16 is secured along the bottom rear marginal edge of the table and the legs 13 and back plate 15 are secured thereto and the parts re-enforced thereby. A bracing strip 17 of metal or other bendable material is wrapped about the rear face of back plate 15 and its end portions 18 are secured to the side faces of the rails

2

14, table 10 and the ends of reenforcing rail 16. This provides for a sturdy machine which is not liable to be broken.

Midway the width of back plate 15 and at its upper edge I have secured a hinge 19. A tiltable lever 20 is secured to the opposite leaf of the hinge 19 for vertical tilting movement longitudinally of the machine. Spaced from the back plate 15 I have provided a transversely extending stripping bar 21 which is secured to the top edges of the side rails 14 and extends parallel with the back plate 15. A multiplicity of apertures 22 are formed downwardly through the stripping bar 21 and are spaced equidistant one from the other. Above the stripping bar 21 I provide a parallel plunger bar 23 which is vertically movable toward and away from the stripping bar 21, and the plunger bar carries a plurality of plungers 24 which depend therefrom forming a bank of plungers, one plunger extending through each aperture 22. Pivotally mounted at the ends of the stripping bar 21 is a U-shaped guide yoke 25. This is provided to guide the movement of plunger bar 23 and limit its upward movement away from stripping bar 21. The guide yokes 25 are tiltable about the pivot pins 26 transversely of the table, thus are movable off the ends of plunger bar 23.

Table 11 is provided with a plurality of apertures 27 positioned in a row transversely of the table and disposed one axially aligned with each plunger 24, and the upper ends of these apertures communicate with sockets 28 which are adapted to receive and hold individual cherries C while the plungers press the pits P from the cherries.

The area defined by the transverse row of sockets 28, the rear portion of the side rails 14 and the back plate 15 comprises a hopper for the cherries to be pitted, and the table 11 is provided with longitudinally extending parallel depressed tracks 29 which communicate at their forward ends with the sockets 28 and extend rearwardly into the hopper. As the cherries C are displaced from the sockets 28, other cherries enter the sockets by rolling down tracks 29 from the hopper.

To assist in displacing the cherries C from the sockets 28, I have provided a lifter bar 30 which carries a plurality of lifters 31, each lifter disposed axially aligned with a plunger and an aperture 27, forming a bank of lifters. Securing strips 32 unite the ends of plunger bar 23 and lifter bar 30 maintaining the bars in a constant spaced parallel relation with the plunger bar above the table and the lifter bar below the table. As plunger bar 23 is moved downwardly, lifter bar 30 is simultaneously moved downwardly, and the bars are moved upwardly simultaneously, thus forming a vertically shiftable unit. A strap 33 is secured at its ends to the plunger bar 23 and in covering relation to lever 20 which has a handgrip 34 at its forward outer end. The machine is thus manually operated and the grip 34 is grasped and the lever 20 tilted vertically, thus causing the plunger bar 23 and lifter bar 30 to move downwardly pressing the plungers 24 through the cherries C and expelling the pits P through apertures 27. On the upward movement of the lever 20 the plungers are moved upwardly through stripping bar 21 and any cherries which may cling to the plungers are stripped off by the bar as the plungers move upwardly through their apertures 22, and the cherries drop into the sockets sometimes bouncing and rolling on down the inclined table; but in the event the cherries remain in the sockets, the lifters 31 move upwardly through apertures 27 and their angular end faces 35 contact the cherries and lift them out of the sockets permitting them to roll down the inclined table. It will be noted that the lower end face of each plunger is serrated to provide means of

3

holding the pit against slipping from beneath the plungers.

Locking strips 36 are pivoted at 37 to the inner face of side rails 14 and are provided with an enlarged head portion 38 adapted to be swung between stripping bar 21 and plunger bar 23 to maintain the plungers 24 in their raised position. Of course, while the lifter bars 31 are extended into the sockets 28, any cherry rolling down the tracks 29 will impinge against the lifters and then as the downward movement is made will be permitted to roll into the sockets 28.

For cleaning purposes, it is only necessary to remove the upper or lower ends of the securing strips 32 and pivot the yokes 25 out of confining relation to plunger bar 23 and the plunger bar and its plungers are separated from the table, as also is the lifter bar and its plungers. The plunger bar may be slid over the grip 34 of the lever 20 and the various parts cleaned and reassembled.

Having thus described my invention, I claim:

A cherry-pitting machine comprising in combination 20 a table inclined longitudinally, a transversely disposed row of spaced sockets in the upper face of said table, each said socket having an aperture extending downwardly through the table, depressed tracks on the upper face 25 of said table and communicating one with each said socket and extending longitudinally of the table upwardly of the sockets, a stripping bar disposed spaced above said sockets and having apertures axially aligned with said first named apertures, a plunger bar parallel

with and above said stripping bar and shiftable toward and away from said stripping bar, depending plungers carried by said plunger bar and extending axially through said second named apertures and normally spaced above 5 said first named apertures, whereby downward movement of said plunger bar will effect movement of the lower ends of said plungers through said sockets and into said first named apertures, a lifter bar disposed beneath the table parallel with said plunger bar and shiftable therewith toward and away from the table, upstanding lifters carried by said lifter bar and axially aligned with said plungers and adapted to move upwardly through said first named apertures into said sockets, said lifters having angled faces disposed at an angle greater than the incline of said table and in the same direction, whereby cherries in the sockets are displaced, and a tiltable lever hingedly carried by the table and operably connected to said plunger bar whereby said plunger bar may be manually shifted in a vertical path.
